UNITED STATES PATENT OFFICE.

ALFRED BAGNALL, OF PHILADELPHIA, PENNSYLVANIA, ASSIGNOR TO SCOTT PAPER COMPANY, A CORPORATION OF PENNSYLVANIA.

Fixture for Supplying Paper, &c., from Rolls.

Specification of Letters Patent.

Patented Aug. 4, 1914.

1,105,951.

Application filed January 5, 1912. Serial No. 669,604.

To all whom it may concern:

Be it known that I, ALFRED BAGNALL, a citizen of the United States, and a resident of the city and county of Philadelphia and State of Pennsylvania, have invented an Improvement in Fixtures for Supplying Paper, &c., from Rolls, of which the following is a specification.

More particularly this invention relates to fixtures in which a roll of paper or other material is supported on a rotary roller or mandrel, so that the paper may be drawn out and detached as required for use.

While the fixture is particularly designed for use with rolls of paper toweling, it may also be used with other materials.

It is the principal object of my invention to prevent the removal of a roll from the mandrel after it has been placed in the fixture, thus making impossible thefts of new or partially used rolls by taking them from the fixture. This object I accomplish by means of an extensible mandrel with suitable locking devices to lock the mandrel in extended position against removal from the frame of the fixture after the roll has been applied, such locking devices being so arranged upon the mandrel as to be inclosed by the roll and thus rendered inaccessible to manipulation until the roll is unwound. The locking device may then be operated to contract the mandrel and remove it from the frame so that a fresh roll may be applied.

The invention also relates to various features of construction and combinations of parts which are fully set forth hereinafter.

Figures 1 and 2 are respectively a longitudinal vertical section and a transverse vertical section taken, the one on line A—A of Fig. 2, and the other on line B—B of Fig. 1; Fig. 3 is a plan view on an enlarged scale of one end of the mandrel showing the spring for controlling the spring-knob; Fig. 4 is a transverse section on the line C—C of Fig. 3; Fig. 5 is a similar view supposing the spring-knob to have been pushed in to the extent indicated by the section line D—D of Fig. 3; Fig. 6 is a perspective view of the mandrel; and Fig. 7 is a similar view of the adjustable bearing for the mandrel spring.

a is a tubular mandrel upon which the roll of paper b is supported. The paper roll usually has a tubular core b' and is slipped upon the mandrel when the latter is removed from the supporting frame. The mandrel a

is provided at one end with a fixed knob c and at the other end with a spring-knob d. The shanks h h of these knobs are inserted in slots e in the ends f f of the housing g, and are provided with enlargements e' e' 60 which form journals fitting bearings e² e² in the ends f. The shanks h h project through the ends f f so that the mandrel may be rotated to unroll the paper. As shown the housing is provided at the back with flanges g' g' for attachment to the wall. The shank h of the knob d is free to move longitudinally in the mandrel and is pressed outward by a spring j in the mandrel, the tension of which spring may be regulated 65 by a sliding bearing k adjusted by a screw m extending through the shank of the fixed knob c. A pin n extending through a slot n' in the bearing k prevents rotation of the bearing and insures its longitudinal movement when it is adjusted by the screw m. On the end of the mandrel which carries the movable knob is a spring o having a slot p, through which extends a screw or pin q, carried by the shank of the movable knob 70 d and extending through a slot a' in the mandrel. The slot p extends longitudinally and is provided at its outer end with an enlarged aperture and terminates at its inner end in a sharp angle p'. The pin q which 75 extends through the slot p has below its head an enlargement q' which loosely fits the enlarged aperture in the outer end of the spring but cannot pass through the length 80 of the slot p. It follows that when the knob 90 d and its shank h are projected, as shown in Figs. 1, 3 and 4, the enlargement q' of the pin q will fit in the enlarged aperture of the spring and the knob d will be held in projected position with its journal e' in the 95 bearing e² of the side of the housing. This is the position occupied by the knob d when a roll of paper is mounted on the mandrel, and while the parts are in this position the mandrel cannot be removed from the housing, since the enlargements e' e', forming the journals, are retained in the bearings e², e², and prevent the shanks of the knobs 100 from being withdrawn through the slots.

In order to press in the knob d and remove 105 the mandrel it is necessary to depress the spring o as the enlargement in the slot p which engages the enlarged portion q' of the pin q acts as a locking device, which can be unlocked only by the manual depression 110

of the spring to free the part q' from the enlargement of the slot.

The spring cannot be manipulated while the roll of paper is on the mandrel, and consequently a roll cannot be removed until it is used or unwound. When the mandrel is empty the spring o is depressed and the knob d is pushed in and turned to move the pin q into the angular portion p' of the slot p . This locks the knob d in retracted position and the mandrel may be removed and a new roll placed in it. The mandrel is then replaced in the slots e and the handle d is turned to release the pin q from the angular portion p' of the slot p . The knob d is then projected and the mandrel is locked in position as before and cannot be again removed until the new roll is used or unrolled. Thus theft by the removal of new or partially used rolls is effectively prevented.

I do not mean to confine myself to the details of construction shown which may be varied without departing from the invention.

What I claim is as follows:

1. In a device for the purposes stated, the combination of a frame having bearing sockets provided with slots, a mandrel provided on its ends with knobs having shanks adapted to pass through the slots in the frame and provided with journals adapted to fit the bearing sockets, said mandrel being extensible, so that its journals may be moved out of the bearing sockets to enable the mandrel to be removed, and manually controlled locking devices carried by the mandrel for locking the same in extended condition.

2. In a device for the purposes stated, the combination of a frame having bearing-sockets provided with slots, a mandrel provided on its ends with knobs having shanks adapted to pass through the slots of the frame and provided with journals adapted to fit the bearing-sockets, one of said knobs being movable longitudinally, and locking devices carried by the mandrel to lock said knob in extended and retracted position.

3. In a device for the purposes stated, the combination of a frame having bearing-sockets provided with slots, a mandrel provided on its ends with knobs having shanks adapted to pass through the slots of the frame and provided with journals adapted to fit the bearing-sockets, one of said knobs being movable longitudinally, and locking devices carried by the mandrel to lock said knob in extended and retracted position, said locking devices consisting of a spring o carried by the mandrel and provided with a slot p hav-

ing an enlarged opening at one end and an angular portion p' at the other end, and a pin q carried by the shank of the movable knob and having an enlargement q' fitting the enlarged opening in the slot of the spring.

4. In a device for the purposes stated, the combination of a frame having bearing-sockets provided with slots, a mandrel provided on its ends with knobs having shanks adapted to pass through the slots of the frame and provided with journals adapted to fit the bearing-sockets, one of said knobs being movable longitudinally, a spring within the mandrel acting to project the movable knob, and locking devices carried by the mandrel to lock said knob in extended and retracted position.

5. In a device for the purposes stated, the combination of a frame having bearing-sockets provided with slots, a mandrel provided on its ends with knobs having shanks adapted to pass through the slots of the frame and provided with journals adapted to fit the bearing-sockets, one of said knobs being movable longitudinally, a spring within the mandrel acting to project the movable knob, means extending through the other knob to adjust the tension of the spring, and locking devices carried by the mandrel to lock said knob in extended and retracted position.

6. In a device for the purpose stated, the combination of a frame, bearing sockets provided with slots carried by said frame, an expansible mandrel having its ends journaled in said sockets, means radially disposed on said mandrel to hold said mandrel from displacement through said slots, and means to lock said holding means in operative position.

7. In a device for the purpose stated, the combination of a frame, bearing sockets provided with slots carried by said frame, an expansible mandrel having its ends journaled in said sockets, means radially disposed on said mandrel to hold said mandrel from displacement through said slots, means to lock said holding means in operative position, and means to lock said mandrel in retracted position to release said holding means, whereby said mandrel may be removed from said sockets.

In testimony of which invention, I hereunto set my hand.

ALFRED BAGNALL.
